UNITED STATES PATENT OFFICE

169,878

MANIPULATIVE TOY

Nathaniel W. Washington, Ephrata, Wash.

Application March 4, 1952, Serial No. 18,764

Term of patent 14 years

(Cl. D34—15)

To all whom it may concern:

Be it known that I, Nathaniel W. Washington, a citizen of the United States, and a resident of Ephrata, county of Grant, and State of Washington, have invented a new, original, and ornamental Design for a Manipulative Toy, of which the following is a specification, reference being had to the accompanying drawing, forming a part thereof.

In said drawing:

Fig. 1 is a front elevational view of a manipulative toy, showing my new design, and with the toy portrayed in a selected one of various configurations which can be obtained by manipulation of the multiple links about the connecting points.

Fig. 2 is a bottom plan view thereof; and

Fig. 3 is a fragmentary perspective view there-

of, showing one of the component pieces from which the links of the toy are made.

I claim:

The ornamental design for a manipulative toy, as shown and described.

NATHANIEL W. WASHINGTON.
